RAILWAY TRAFFIC CONTROLLING APPARATUS

Ronald A. McCann, Swissvale, Pa., assignor to
The Union Switch & Signal Company, Swiss-
vale, Pa., a corporation of Pennsylvania

Application July 22, 1931, Serial No. 552,366

14 Claims. (Cl. 246—3)

My invention relates to railway traffic controlling apparatus for governing traffic over a railway switch, and more particularly to apparatus for insuring reliable operation of the approach 5 or route locking for a railway switch. Other features of my invention will appear as the specifications progress.

The apparatus of my invention is an improvement over that disclosed in the copending applications Serial No. 125,659, filed July 29, 1926, by Herbert A. Wallace for Railway traffic controlling apparatus; and Serial No. 313,772, filed October 20, 1928, by Howard A. Thompson for Multiple control apparatus.

15 I will describe one form of my invention, and will then point out the novel features thereof in claims.

The accompanying drawing is a diagrammatic view showing one form of my invention. Referring to the drawing the reference characters 1 and 2 designate the traffic rails of a stretch of railway track which I will call the "main" track. These rails are divided by the usual insulated rail joints 3 into track sections RT, !T and LT 25 of which the middle track section !T may be termed a "detector" track section and the two outer track sections RT and LT may be termed "approach" track sections. Located in the detector section !T is a switch S which when reversed directs traffic from the main track into a passing siding PS.

Each track section of the main track is provided with a conventional track circuit comprising a source of current such as a battery and a 35 track relay which is designated by the reference character R plus a prefix corresponding to the track section. Track battery 4 for the track section !T is connected across the rails 5 and 6 of the siding PS while these rails, at the fouling point, are connected by wires 7 and 8 to the rails 1 and 2, respectively, of the main track at the left-hand end of section !T. As the track relay !TR is connected across the rails 1 and 2 at the right-hand end of section !T, it follows that 45 battery 4, the rails of the siding up to the fouling point, the rails of the main track of the section !T and the track relay !TR are connected in series. For the approach track sections the track battery is connected across the rails adjacent one end and the track relay across the rails adjacent the opposite end of the section in the customary manner.

Power for operating the apparatus and circuits of my invention may be obtained from any 55 convenient alternating current or direct current source but which is not shown in the figure. In this description I shall consider that the current source supplies direct current and that the relays are all direct current relays. The positive terminal of the source is designated by the

reference character BL while the negative terminal is designated by the reference character CL.

The switch S is preferably provided with a switch operating machine SM which is controlled by a switch controlling relay W, and which relay in turn is controlled by the relays 6X and 6Y. The relays 6X and 6Y are themselves controlled from some remote control point, such for example as a dispatcher's office, by a remote control system of a convenient type. As the switch machine SM together with its operating circuits form no part of my invention, they are omitted from the drawing for the sake of clearness. It will be understood that the switch machine SM is of one of the standard types and that the operating circuits for the switch machine are controlled by the polarized armature of the switch controlling relay W in accordance with the usual practice. That is to say, when the relay W is energized with current of a normal polarity the 20 switch machine SM positions the switch S for traffic on the main track, while when the relay W is energized with current of a reverse polarity the switch S is positioned for traffic to and from the siding PS. The relay W is of the direct current polarized type wherein the polarized armature will remain in the position to which it was last moved whenever its winding becomes deenergized, and sufficient contact pressure will be maintained by the armature with its contacts to 25 hold properly closed the operating circuit passing therethrough.

The circuit for energizing the relay W with current of normal polarity starts at the positive terminal BL and includes the back contact of 35 armature 9 of relay 6Y, front contact of armature 10 of relay 6X, winding of relay W, front contact of armature 11 of a route locking relay RMR to be described later, wire 12, front contact of armature 13 of a second route locking relay LMR to be 40 described later also, front contact of armature 14 of the track relay !TR of the detector track section !T, front contact of armature 15 of relay 6X, back contact of armature 16 of relay 6Y and to the negative terminal CL. With relay 6Y energized and its armatures 9 and 16 brought into engagement with front contacts and the relay 6X deenergized so that its armatures 10 and 15 engage back contacts then the current supplied to the relay W by the above circuit is of a reverse 45 polarity. The control system for selectively controlling the relays 6X and 6Y forms no part of my invention and is not shown in the drawing. It will be understood that these relays may be controlled by some one of the remote control systems which are in general use. As a matter of fact instead of making use of relays 6X and 6Y as the means for controlling the current supplied to the switch controlling relay W this circuit may be controlled by circuit controllers operated by a 50 55 60

lever of an interlocking machine. It follows then, that the current supplied to the relay W is of normal or reverse polarity according as relay 6X or 6Y is selected, or if a lever is the controlling element according as that lever is in a normal or a reverse position, and, consequently, the switch S will occupy its normal or reverse position according to the relay selected or according to the position of the controlling lever. It will be noted that the circuit for the relay W cannot be closed unless the detector track section 1T is unoccupied and unless the route locking relays RMR and LMR are both energized.

Traffic moving from the right to the left is controlled by the signals L2A and L2B, and will be spoken of in this description as westbound traffic. Traffic moving from the left to the right on the main track is controlled by the signal R2A, while traffic moving from the siding PS to the right is controlled by the signal R2B. Traffic moving from the left to the right will be spoken of in this description as eastbound traffic. These signals may be of any standard type and are here shown as semaphore signals each capable of displaying a stop or clear indication. The operating circuit for each signal is controlled by a signal controlling relay designated in the drawing by the reference character H with a prefix corresponding to the signal. These operating circuits will be readily understood by an inspection of the drawing and it is thought that it is sufficient to say that with a signal controlling relay H energized the operating circuit for the associated signal is closed to clear that signal. The system for controlling the signal controlling relays also forms no part of my invention and is omitted from the figure. It will be understood that these signal controlling relays may be controlled by the same remote control system that controls the relay 6X and 6Y and that the energizing of the signal controlling relay is governed jointly by the remote control system and by traffic conditions in advance of the signal in accordance with standard practice.

An indicating relay RGP is associated with the eastbound signals R2A and R2B. This relay RGP is normally energized by a circuit from positive terminal BL through a controller 17 operated by the signal R2B as indicated by a dotted line and which controller is closed only when the signal R2B indicates stop, circuit controller 18 operated by the mechanism of signal R2A and closed only when that signal is in its stop position, winding of relay RGP and to the negative terminal CL. An indicating relay LGP is associated with signals L2A and L2B and is energized by a circuit including the controllers 19 and 20 operated at the signals L2A and L2B, respectively, and which controllers are closed only when the associated signal occupies its stop position. It follows then that these indicating relays RGP and LGP are both normally energized and become deenergized whenever an associated signal is cleared to permit a traffic movement over the switch S.

The apparatus includes an eastbound route locking relay RMR and a westbound route locking relay LMR. The relay RMR is provided with a normally closed energizing circuit that passes from the positive terminal BL through the front contact of armature 21 of the relay RGP, wire 22, front contact of armature 23 of the track relay RTR for the approach track section RT, contact 24 of circuit controller L connected to and operated by the switch S and which contact is closed

when the switch is set for traffic on the main track, wire 25, front contact of armature 26 of the detector track relay 1TR, wire 27, winding of relay RMR and to the negative terminal CL. This relay is provided with a stick circuit that branches from wire 22 and includes a wire 28, front contact of its own armature 29 and the winding of the relay to the negative terminal CL. A pick-up circuit is provided for the relay RMR that branches from the wire 22 along wires 28 and 33, front contact of armature 32 of a slow-acting relay 1TZ when that relay is energized as will be described later, wire 31, back contact of armature 30 of the track relay LTR when that relay is deenergized, wire 25, front contact of armature 26 of relay 1TR, wire 27 and winding of relay RMR to the negative terminal CL. The relay RMR can be energized by still another circuit that is the same as before traced from positive terminal BL up to the wire 33, thence along wire 36, front contact of armature 35 of a time element device 1TE to be described later, wires 34 and 25 and then as before pointed out to the winding of the relay RMR.

The route locking relay LMR is provided with a circuit network similar to that described for the relay RMR. The normal energizing circuit for the relay LMR passes from the positive terminal BL through the front contact of armature 37 of relay LGP, wire 38, front contact of armature 39 of the track relay LTR for the approach track section LT, wire 40, front contact 41 of the detector track relay 1TR, winding of relay LMR and to the negative terminal CL. A stick circuit for relay LMR branches from the wire 38 and extends along the wire 42 and the front contact of its own armature 43 to the winding of the relay and to the negative terminal CL. A pick-up circuit extends from the wire 38 along wires 42 and 47, front contact of armature 46 of the slow-acting relay 1TZ when that relay is energized, wire 45, back contact of armature 44 of the track relay RTR when that relay is deenergized, wire 40, front contact of armature 41 and the winding of relay LMR to the negative terminal CL. The relay LMR also can be energized by a circuit that is the same as that just traced up to the wire 47, thence through the front contact of armature 49 of the time element device 1TE, wire 48 to the wire 40 and then as before pointed out to the winding of the relay LMR. When the switch S is set for the siding and the contact 24 of the controller L moved to its reverse position, that is, to the lower position in the drawing, a by-pass circuit is closed around the back contact of the armature 44 of relay RTR. This by-pass circuit extends from wire 45 along wire 51, contact 24 and wire 50 to the wire 40. Thus each of these route locking relays is normally energized and is deenergized whenever a signal governing traffic in the same direction as that with which the relay is associated is cleared. When the route locking relay is energized it closes a contact in the circuit to the switch controlling relay W as previously pointed out and when it is deenergized the circuit to the switch controlling relay is opened to prevent operation of the switch S. The function of the circuit network associated with each route locking relay will be fully pointed out when the operation of my system is described.

The slow-acting relay 1TZ is provided with an energizing circuit that passes from the positive terminal BL through the back contact of armature 52 of the detector track relay 1TR when that relay is deenergized, resistance 53, winding of re-

lay !TZ and to the negative terminal CL. Once the relay !TZ is picked up the resistance 53 is shunted by a path through a front contact of its own armature 54. As is well-known the pick-up period of a direct current relay is in a measure proportional to the value of the current applied to its winding. With a given source of current the value of the resistance 53 will thus determine the time required to magnetically saturate the cores of the relay !TZ sufficiently to lift the armature of the relay into engagement with its front contacts, and thus it follows that the pick-up period of the relay !TZ is in this case determined by the resistance 53 and can be made long or short by selecting the relative value of the resistance. I prefer to provide the resistance 53 with such a value that the pick-up period of the relay !TZ is relatively long, say five seconds. In direct current relays provided with slow-releasing characteristics the release period is increased when the energizing current is increased. The relay !TZ is provided with slow-release characteristics and thus the shunting of resistance 53 as the relay is picked up establishes full energization of the relay 25 and thereby insures a full release period for the relay. Thus I have provided a combination whereby the relay !TZ will not pick up its armature until some time after its energizing circuit is closed and then when once the relay is picked up 30 its energization is materially increased so that the relay has a relatively long release period.

The apparatus also includes a time element device !TE. This time element device may take different forms several of which are well-known to the art. In this instance I prefer to employ a time element device of the relay type. Such relays are in general use and need not be described further than to say that this relay will not operate its armatures for some predetermined interval of 40 time after the energizing circuit for its winding is closed. In this description I shall speak of the predetermined time interval that the winding of the relay !TE must be energized before its armatures 35 and 49 are operating as being five minutes. It will, of course, be understood that this time interval can be made to suit the local conditions. The relay !TE is provided with two energizing circuits one of which is associated with eastbound traffic and the other with westbound 50 traffic. The circuit associated with eastbound traffic starts at the positive terminal BL at the armature 21 of relay RGP and includes the wire 28, back contact of armature 29 of the relay RMR, wire 57, front contact of armature 55 of the track 55 relay !TR, winding of the relay !TE and to the negative terminal CL. The circuit associated with westbound traffic starts at the positive terminal BL at armature 37 of relay LGP and includes wires 38 and 42, back contact of armature 43 of the relay LMR, wires 56 and 57, front contact of armature 55 and winding of relay !TE to the negative terminal CL. It follows that whenever a route locking relay is deenergized and the associated indicating relay is energized a circuit is 60 closed to the winding of the time element relay !TE.

In describing the operation of my invention I shall assume that the parts of the apparatus are in the position in which they are shown in the 70 drawing and that an eastbound train is to be advanced over the switch on the main track. The remote control system will first function to select the relay 6X so as to position the switch S for the main track. Then as the signal controlling relay R2AH is energized the signal R2A

is cleared. The clearing of signal R2A deenergizes the relay RGP to open the circuit to the route locking relay RMR at the armature 21. With relay RMR once deenergized no movement of the switch can take place due to the fact that the control circuit for the relay W is now open at the armature 11 of the route locking relay RMR. As the eastbound train advances into the approach track section RT and shunts the track relay RTR the energizing circuit to the relay RMR is also opened at the armature 23. When the eastbound train enters the detector track section !T and shunts the relay !TR the signal R2A will, of course, be set at stop by the customary control circuit not disclosed herein, and the circuit to the relay RGP closed thereby to reenergize that relay. Although the relay RGP is now picked up no circuit is completed to the route locking relay RMR as long as the train occupies the detector track section as all pick-up circuits leading to the relay RMR are controlled by the front contact of armature 26 of the detector track relay !TR. When the eastbound train advances east through the sections RT and !T and vacates these sections the relays RTR and !TR will be 25 in turn picked up and the normal energizing circuit to the route locking relay RMR closed to re-energize that relay. That is to say that as soon as the eastbound train vacates the detector track section !T the route locking is released and the 30 switch S is free to be operated.

As the detector track circuit is shunted by the eastbound train and the relay !TR deenergized, the circuit to the slow-acting relay !TZ is closed and after a period which we have taken as five 35 seconds, it lifts its armatures into engagement with the front contacts. When the eastbound train shunts the westbound approach track section LT, a pick-up circuit is established for the relay RMR which is not completed, however, until the rear of the train vacates the section !T and the track relay !TR is reenergized. Although this pick-up circuit for relay RMR was previously pointed out it is thought that it might be well to again trace it from positive terminal BL through 45 armature 21, wires 28 and 33, armature 32, wire 31, back contact of armature 38, front contact of armature 26, wire 27, winding of relay RMR and to the negative terminal CL. This circuit will be closed only during the release period of the relay !TZ due to the fact that as the track relay !TR picks up to close this circuit for the relay RMR at the front contact of armature 26 it also opens the energizing circuit to the relay !TZ at the back contact of the armature 52. In case 55 a second eastbound train has entered the approach track section RT before the first eastbound train vacates the section !T, then when the first train vacates section !T and enters section LT the route locking relay RMR would 60 be reenergized and the route locking released by this pick-up circuit just traced. It is understood, of course, that the signal R2A is set at stop and relay RGP energized behind the first train. Although this pick-up circuit for relay 65 RMR is closed only during the release period of relay !TZ, the relay RMR once energized will be retained energized by its stick circuit.

In the case where the switch is reversed and the signal R2B cleared for a train to advance 70 east from the siding PS the circuit to the route locking relay RMR is opened at the contact 24 as the switch is positioned for the siding, and also by the relay RGP as the signal R2B is cleared. As the train advances east from the 75

siding and signal R2B set at its stop position the normal circuit for energizing relay RMR still will be held open at the contact 24 and the route locking still retained effective. As this train enters the detector track section and shunts 5 the relay LTR the energizing circuit to the slow-acting relay TZ is closed and after its pick-up period of five seconds the armature 32 engages the front contact that is included in the pick-up 10 circuit previously traced to the relay RMR. As this train enters the track section LT and vacates the section T this pick-up circuit for relay RMR is completed and that relay reenergized after which it is retained energized by its stick 15 circuit, and thus the switch S is released from the route locking.

The operation of the route locking for a west-bound train is similar to that described for east-bound traffic except when a movement is made 20 into the siding. As the switch S is set for the siding the contact 24 is moved to its reverse position. As a west bound train occupies the detector track section the relay TZ is energized and picked up at the end of its five second pick-up period and a circuit is formed from the positive terminal BL through the armature 37 of relay LGP, wires 38, 42 and 47, front contact of armature 46 of relay TZ, wires 45 and 51, contact 25 24, wires 50 and 48, front contact of armature 41 when relay LTR is picked up, winding of relay LMR and to the negative terminal CL. It follows that as the westbound train moves into the siding and vacates the detector track section T so that relay LTR is picked up an energizing 30 circuit to the route locking relay LMR is closed during the release period of the relay TZ. With relay LMR once picked up it is held energized by its stick circuit and thus the route locking for the switch S is released as soon as this west-bound train moving into the siding vacates the section T. It is to be noted that an eastbound 35 train entering the approach track section LT and shunting the track relay LTR does not deenergize the westbound route locking relay LMR. Under 40 this traffic condition the relay LMR is retained energized by its stick circuit due to the fact that the signal indicating relay LGP will be retained energized. In like manner a westbound train entering the approach track section RT will not 45 deenergize the eastbound route locking relay RMR as its stick circuit is completed at the front contact of the armature 21 of the signal indicating relay RGP.

The relatively long pick-up period provided 50 for the relay TZ makes this relay practically immune from momentary interruptions of the detector track circuit as it requires that the detector track relay be opened for a definite period of time before it will function to set in motion the releasing of the route locking. This 55 insures against the possibility of the release of the route locking for a given direction of traffic movement by a momentary shunt of the detector track circuit at a time when the approach track section for the opposite direction is occupied. Assume for example, that the switch S is set for the siding and a westbound train is approaching in the track section LT while at the same time an eastbound train occupies the section RT to 60 the rear of the signal R2A. A momentary shunt of the detector track section T for any cause whatsoever will close the energizing circuit to the relay TZ and if that relay should immediately pick up the route locking would be released when 65 the momentary shunt on the detector track sec-

tion is removed and its track relay reenergized. The shunting of the detector track section will set the westbound signal at stop and the relay LGP will become reenergized and if the relay TZ is now up the pick-up circuit for the relay 5 LMR is closed during the release period of the relay TZ. Such a false release of the route locking where the switch is controlled by a remote control system may result in the dispatcher acting to change the position of the switch in 10 the face of an approaching train. With the relay TZ requiring a pick-up period of some definite length, say five seconds, then any momentary shunting of the detector track section will not result in a release of a route locking. By the 15 shunting of the resistance 53 as the relay TZ is picked up so that the energization of this relay is materially increased a slow-release period is readily provided for the relay TZ that is of sufficient duration to insure reliable operation 20 of the route locking relay when that relay is being reenergized by a circuit that is closed only during the release period of the relay TZ.

The function of the time element relay TE is to provide the release of the route locking when 25 a signal is returned to the stop position before it is accepted by a train. As previously pointed out when the signal R2A is cleared, the relay RMR is deenergized. Should the signal R2A be now set at stop by the deenergizing of the signal 30 controlling relay RA2H by the dispatcher, or if deenergized otherwise, without an eastbound train having advanced past the signal and while the train still occupies the approach track section RT the energizing circuit associated with 35 eastbound traffic for the relay TE is completed and after a predetermined interval, which in this discussion we have assumed to be five minutes, the armature 35 engages its front contact. As the armature 35 engages its front contact then an 40 energizing circuit for the relay RMR can be traced from positive terminal BL through armature 21, wires 28, 33 and 36, armature 35, wires 34 and 25, armature 26, wire 27, winding of the relay RMR and to the negative terminal CL. It 45 follows that with a signal cleared and the route locking rendered effective the time element device TE will release the route locking after a predetermined interval in the event the signal is set at stop before the train has accepted the 50 signal, the time interval being made of such duration that an approaching train will have come to a stop to the rear of the signal or will be over the switch and gone before the switch is moved. The relay TE functions to release 55 the route locking relay LMR in connection with westbound traffic in the same manner as has just been described in connection with east-bound traffic where the route locking relay RMR is reenergized.

Such a system as here disclosed provides a normal route locking circuit that becomes effective as soon as a signal is cleared for the route and which will be released as soon as the track circuits involved are vacated. The route locking circuit being controlled by front contacts of the track relays a momentary shunting of the detector track section will not release the route locking. As the clearing of the signal rendered the route locking effective the loss of shunt of the approach 70 track section will also not effect a release of the route locking. As a matter of fact a simultaneous combination of a loss of shunt for the approach track section and a shunting of the detector track section will not bring about the re- 75

lease of the route locking circuit. Under traffic conditions that prevent the normal route locking circuit from functioning to release the route locking relay a pick-up circuit controlled by a slow-acting relay operates to reenergize the route locking relay and this slow-acting relay is also immune from false operation resulting from a momentary shunting of the detector track section. The utility of such a route locking circuit will be apparent to all familiar with the art.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In combination, a stretch of railway track including an approach track section and a detector track section, a switch leading from the detector track section, a signal to govern the movement of traffic from the approach track section into the detector track section, a track relay for each said track section, an indicating relay energized when the signal is at stop position, a route locking relay to control the operation of the switch arranged to permit operation of said switch when energized and to prevent operation of the switch when deenergized, and a circuit to energize said route locking relay including a front contact of the indicating relay and a front contact of each said track relay.

2. In combination, a stretch of railway including a railway switch and divided into a track section adjacent the switch and a track section in advance of the switch, a signal to govern traffic over the switch, a route locking relay to control the operation of the switch arranged to permit the operation of the switch when energized and to prevent the operation of the switch when deenergized, means responsive to the clearing of the signal to deenergize said relay, a normally deenergized slow-acting relay, circuit means responsive to a train occupying the track section adjacent the switch to energize said slow-acting relay arranged to pick up said relay only after the energizing circuit has been closed a definite period of time, and a circuit including a contact closed only when the track section in advance of the switch is occupied and including also a front contact of the slow-acting relay to at times energize the route locking relay.

3. In combination, a stretch of railway including a switch and divided into a track section adjacent the switch and a track section in advance of the switch, a signal to govern traffic through the stretch, a track relay for each section responsive to traffic conditions of the section, a route locking relay to control the operation of the switch arranged to permit operation of the switch when energized and to prevent operation of the switch when deenergized, means to deenergize said route locking relay when the signal is cleared, a normally deenergized relay, a circuit to energize said relay when a train occupies the track section adjacent the switch arranged to pick up said relay only after the relay has been energized a given interval of time; and another circuit means including a front contact of the track relay for the section adjacent the switch, a back contact of the track relay for the section in advance of the switch and a front contact of the normally deenergized relay to energize the route locking relay.

4. In combination, a stretch of railway including a switch and divided into a track section adjacent the switch and a track section in advance of the switch, a relay to control the operation of the switch arranged to permit operation of the switch when energized and to prevent operation of the switch when deenergized, an electroresponsive device arranged to operate a contact when energized, a circuit means rendered effective to energize said device only when the track section adjacent the switch is occupied and arranged to cause operation of the contacts of said device a given interval of time after said device becomes energized, and a circuit closed only when the track section in advance of the switch is occupied and including also a contact of said electroresponsive device to at times energize the said relay.

5. In combination, a stretch of railway including a switch and divided into a track section adjacent the switch and a track section in advance of the switch, a first relay to control the operation of the switch arranged to permit operation of the switch when energized and to prevent operation of the switch when deenergized, a second relay, a circuit closed only when the track section adjacent the switch is occupied to energize the second relay and arranged to cause said relay to be picked up a given interval of time after said circuit is closed; and another circuit closed only when the track section in advance of the switch is occupied and the second relay is picked up to energize said first relay and thereby permit operation of said switch.

6. In combination, a stretch of railway arranged to provide different traffic routes and including a first and a second track section, a first relay to control the selecting of said traffic routes arranged to permit a change of routes when energized and to prevent a change of the route when deenergized, a second relay, a circuit closed in response to a train occupying the first track section to energize the second relay and arranged to cause said relay to be picked up a given interval of time after said circuit is closed, and another circuit closed by the train vacating the first track section and occupying the second track section and by the picking up of the said second relay to energize said first relay and thereby permit a change in the routes.

7. In combination, a stretch of railway including a detector track section, a switch leading from the detector track section, a route locking relay to control the operation of said switch arranged to permit operation of the switch when energized and to prevent operation of the switch when deenergized, means to at times deenergize said route locking relay, a normally deenergized slow-release relay, a circuit effective to energize said slow-release relay when a train occupies said detector track section arranged to pick up said relay only after said circuit has been closed a definite period of time, means adapted to increase the energization of said slow-release relay after it is picked up to thereby insure a full release period for said relay, and a second circuit effective to energize said route locking relay during the release period of said slow-release relay.

8. In combination, a stretch of railway including, a detector track section, a switch leading from said track section, a track circuit including a track relay for said track section, a route locking relay to control the operation of the switch arranged to permit operation of the

switch when energized and to prevent operation of the switch when deenergized, means to deenergize at times said route locking relay, a normally deenergized slow-release relay, circuit 5 means including a resistance controlled by said track relay to energize said slow-release relay effective to pick up said relay only after said track relay has been shunted a given period of time, means to shunt said resistance and thereby 10 insure a full release period for said slow-release relay when said relay is once picked up, and a circuit including a front contact of said track relay effective to energize said route locking relay during the release period of said slow-release 15 relay.

9. In combination, a stretch of railway track divided into a detector track section and two approach track sections including one adjacent each end of said detector track section, a track 20 switch leading from the detector track section, a signal for governing the movement of traffic from one approach track section into the detector track section, a track relay for the detector track section, a slow pick-up relay controlled by said 25 track relay, a locking relay for said switch; a plurality of circuits for said locking relay, including a pick-up circuit closed only when said one approach track section is unoccupied, a second pick-up circuit controlled by said slow pick- 30 up relay and closed only when the other approach track section is occupied, and a stick circuit including a front contact of the locking relay, each of said circuits also including a contact closed only when said signal indicates stop; and means 35 controlled by said locking relay for controlling said switch.

10. In combination, a stretch of railway track divided into a detector track section and two approach track sections including one adjacent each 40 end of said detector track section, a track switch leading from the detector track section, a signal for each direction for governing the movement of traffic from the adjacent approach track section into the detector track section, a track relay 45 for the detector track section, a slow pick-up relay controlled by said track relay, a locking relay for each direction for said switch; a plurality of circuits for each locking relay, including a pick-up circuit closed only when the approach 50 track section for the corresponding direction is unoccupied, a second pick-up circuit controlled by said slow pick-up relay and closed only when the approach track section for the opposite direction is occupied, and a stick circuit including 55 a front contact of such locking relay, each of such circuits also including a contact closed only when the signal for the corresponding direction indicates stop; and means controlled by said locking relays for controlling said switch.

60 11. In combination, a stretch of railway track divided into a detector track section and two approach track sections including one adjacent each end of said detector track section, a track switch leading from the detector track section, a signal 65 for governing the movement of traffic from one approach track section into the detector track section, a track relay for the detector track section, a slow pick-up relay controlled by said track relay, a locking relay for said switch; 70 a plurality of circuits for said locking relay, including a pick-up circuit closed only when said one approach track section is unoccupied, a second pick-up circuit controlled by said slow pick-up relay and closed only when the other ap-

proach track section is occupied, a third pick-up circuit closed if the locking relay remains deenergized for more than a predetermined time interval, and a stick circuit including a front contact of the locking relay, each of said circuits also including a contact closed only when the signal indicates stop; and means controlled by said locking relay for controlling said switch. 5

12. In combination, a stretch of railway track divided into a detector track section and two approach track sections including one adjacent each end of said detector track section, a track switch leading from the detector track section, a signal for governing the movement of traffic from one approach track section into the detector track 15 section, a track relay for the detector track section, a slow pick-up relay controlled by said track relay, a locking relay for said switch; a plurality of circuits for said locking relay, including a pick-up circuit closed only when said one approach track section is unoccupied, a second pick-up circuit controlled by said slow pick-up relay and closed only when the other approach track section is occupied, and a stick circuit including a front contact of the locking relay, each of said circuits also including a contact closed only when said signal indicates stop, and each of said circuits except the stick circuit also including a front contact of said track relay; and means controlled by said locking relay for controlling said switch. 20 25

13. In combination, a stretch of railway track divided into a detector track section and two approach track sections including one adjacent each end of said detector track section, a track switch leading from the detector track section, a signal for governing the movement of traffic from one approach track section into the detector track section, a locking relay for said switch, a pick-up circuit for said locking relay closed only 40 when the signal indicates stop and said one approach track section is unoccupied, a second pick-up circuit for said locking relay closed in response to the movement of a train completely 45 out of the detector track section into the other approach track section, a stick circuit for said locking relay closed when said relay is picked up and the signal is at stop, and means controlled by said locking relay for controlling said switch. 50

14. In combination, a stretch of railway track divided into a detector track section and two approach track sections including one adjacent each end of said detector track section, a track switch leading from the detector track section, a signal for governing the movement of traffic from one approach track section into the detector track section, a locking relay for said switch, a pick-up circuit for said locking relay closed 55 only when the signal indicates stop and said one approach section is unoccupied, a second pick-up circuit for said locking relay closed in response to the movement of a train completely out of the detector track section into the other approach track section, a third pick-up circuit for said locking relay closed when said signal indicates stop if the locking relay remains deenergized for more than a predetermined time interval, a stick circuit for said locking relay closed when said locking relay is picked up and the signal indicates 65 stop, and means controlled by said locking relay for controlling said switch. 70
